UNITED STATES PATENT OFFICE.

PIERRE SYLVAIN GAURIAT, OF PARIS, FRANCE, ASSIGNOR TO ETABLISSEMENTS CONTINSOUZA (SOCIETE ANONYME), OF PARIS, FRANCE.

SUPPORTING DEVICE FOR CINEMATOGRAPHIC APPARATUS.

1,418,640.

Specification of Letters Patent. Patented June 6, 1922.

Application filed March 15, 1920. Serial No. 366,093.

To all whom it may concern:

Be it known that I, PIERRE SYLVAIN GAURIAT, citizen of the French Republic, residing at Paris, Department of the Seine, 5 in France, and whose post-office address is 9 and 13 Rue des Envierges, have invented certain new and useful Improvements in Supporting Devices for Cinematographic Apparatus; and I do hereby declare the following to be a full, clear, and exact description of the invention, such as will enable others skilled in the art to which it appertains to make and use the same.

This invention has for its object a supporting device for cinematographic apparatus, which finds its principal application to apparatus in which the protecting boxes containing the reels of film are joined to the body itself of the apparatus.

20 The invention consists in mounting the lower protecting box of cylindrical form on a foot presenting a supporting surface of the same form so as to be able to communicate to the whole of the apparatus angular movements of fixed amplitude.

In the accompanying drawings:—

Figure 1 represents a side view with a partial section through the lower box of a cinematographic apparatus provided with a support according to the invention.

Figure 2 is a view similar to that shown in Figure 1 representing the apparatus in an inclined position.

If reference be made to Figures 1 and 2, it will be seen that the body of the apparatus is represented by 1, and is prolonged by two cylindrical parts 2 and 3, forming protecting boxes for the reels of film. The lower cylinder 3 is mounted on a foot or support 4 having a supporting surface of cylindrical form. In the constructional form shewn, the cylinder 3 has one or more slots 5, situated in one or more planes at right angles to the axis of the cylinder and traversed by pins or bolts 6 having heads 7 and screwed

into the foot 4. The length of the slots 5 is calculated so as to permit of fixed inclinations of amplitude of the cinematographic apparatus.

In order to regulate the inclination of the 50 optical axis of the cinematographic post, it suffices to exert a certain pressure on the whole of the apparatus, so that the lower cylinder 3 slides on the supporting foot 4. Any suitable locking system may be em- 55 ployed for fixing the apparatus in the desired position, and it is quite evident that the mode of guiding the lower cylinder 3 on the foot 4 which has been represented is only given by way of example, and any other 60 suitable mode of guiding might be employed.

The construction herein described is particularly advantageous in the cinematographic art. For instance it will be noted that the arrangement allows an angular displacement of the optical axis of the projecting post in a vertical plane, which displacement has no effect on the two axes of the view projected on the screen; that is to say the long sides remain horizontal and the 65 short sides vertical irrespective of the position of the optical axis, assuming of course, that the foot of the support or base stands on a horizontal plane.

Claim.

75 In a cinematographic apparatus, the combination with an upper and lower circular film protecting receptacle forming a unitary structure with said apparatus, of a base for said apparatus provided with a semi-circular seat for receiving the lower curved edge of the lowermost receptacle, a circumferential slot formed in said lower edge and adjustable fastenings passing through said slot and secured in the base for adjustably 80 mounting the apparatus on said base to swing about the axis of said lowermost receptacle.

85 In testimony whereof I affix my signature.

PIERRE SYLVAIN GAURIAT.
